UNITED STATES PATENT OFFICE.

IRA D. BATE, OF WEST JEFFERSON, OHIO.

GATE-OPERATING MECHANISM.

1,307,804.

Specification of Letters Patent. Patented June 24, 1919.

Application filed August 19, 1918. Serial No. 250,453.

To all whom it may concern:

Be it known that I, IRA D. BATE, a citizen of the United States, residing at West Jefferson, in the county of Madison and State 5 of Ohio, have invented certain new and useful Improvements in Gate-Operating Mechanism, of which the following is a specification.

This invention relates broadly to gates, 10 and has particular reference to improved mechanism for effecting the opening and closing movements of a gate in a simple and convenient manner, the mechanism being of such construction that the gate may be 15 swung from an open to a closed position or vice versa with but a minimum of manual exertion.

The primary object of the invention rests in an attachment for gates of the type which 20 are mounted for swinging movement and normally disposed when in closed position to extend transversely of roadways or the like, whereby through the use of the attachment, the gate will be capable of being 25 opened or closed without requiring one approaching the same in a vehicle to dismount from the latter in order to operate the gate, the mechanism being formed to include a plurality of pivoted arms, disposed to extend substantially parallel with the roadway, and provided with flexible connections 30 leading to a pivoted and weighted gate operating member, said arms being disposed on both sides of the gate, so that by oscillating either of said arms, said weighted member will be oscillated in a simple and convenient manner to effect coöperative movement 35 on part of the gate.

Another object resides in the novel construction and organization of the gate operating mechanism, whereby said mechanism will be so balanced and arranged that a simple and easy operation of the mechanism will be sufficient to swing the gate 45 from one operative position to another, and to construct the mechanism in such manner that the gate will be substantially locked in either its open or closed position.

With these and other objects in view, as 50 will appear as the description proceeds, the invention accordingly consists in the novel features of construction, combination of

elements, and arrangement of parts, herein-after fully set forth in the following description and having the scope thereof 55 pointed out in the appended claim.

In the drawings, forming a part of this specification, similar characters of reference denote like and corresponding parts throughout the several views thereof, and in 60 which:

Figure 1 is a perspective view of the gate operating mechanism comprising the preferred embodiment of the present invention.

Fig. 2 is a top plan view thereof, 65

Fig. 3 is a sectional view disclosing the gate in its open position,

Fig. 4 is a perspective view of the weighted gate operating member,

Fig. 5 is a detail sectional view, disclosing 70 the manner of adjusting the weight upon said member.

In the form of my invention disclosed in the accompanying drawing, the gate operating mechanism A is employed in connection 75 with a gate structure B, which latter in this instance consists of a plurality of longitudinally extending bars 1, which are rigidly united in spaced relation by means of substantially vertical upright braces 2. One 80 end of the gate is provided with eyes 3, which are adapted to receive pintles 4 mounted upon a stationary upright post 5. By means of this construction it will be seen that the gate is capable of swinging movement across a roadway 6, so as to either open or close the latter to travel. At this juncture, it is advisable to state that the construction *per se* of the gate does not form 85 an essential feature of this invention, but 90 that any other gate may be employed with equal facility so long as it is capable of swinging movement. It is further essential, however, that the gate does not sag or drag 95 across the roadway when the same is being operated, as will appear hereinafter.

Mounted contiguous to the post 5 is a frame structure 7, to which is pivotally connected as at 8 an oscillatory gate operating member 9, which latter in this instance being of rod formation. Suitably carried by the member 9, intermediately of its ends, is a depending bracket 10, to the lower end of which is pivotally connected a link connec-

tion 11, the other end of the latter being bent upon itself as at 12, and formed to terminate in a downwardly extending portion 13. A bracket 14 is detachably carried by one of the bars 1 of the gate B, and is formed with a horizontally extending apertured shelf portion 14', which is adapted to receive the downwardly extending end 13 of the link connection 11. By virtue of this construction it will be manifest that movement on part of the gate member 9 in a substantially vertical direction will be cooperatively transmitted to effect horizontal swinging movement on part of the gate structure B.

In order to lock the gate against movement, when the same occupies a closed position, the member 9 is provided with a depending finger 15, which is adjustable lengthwise of said member so that its lower offset end 16 will engage with the link connection 11. This maintains the latter substantially rigid and prevents elevation thereof, so that undue pressure directed upon the gate to open the same will be overcome by the rigid relation existing between said link connection and the member 9. In other words, such pressure would be directly exerted upon the pivot point 8 of the member 9, so that oscillatory movement on part of the latter will be prevented, thus preventing undue movement on part of the gate. This construction automatically serves to lock the gate in its closed position without involving the assistance of outside fastening means, and prevents the gate from being opened by the action of animals or other undue influences.

The end of the member 9, opposite the pivoted end 8, is provided with an adjustable weight 17, which is employed to counterbalance the weight of the gate structure B when the latter is being operated, and to render its movement simple and easy to execute. By adjusting the weight upon the member, the mechanism A may be adapted to gates of different proportions, and yet will maintain the nicety of adjustment and control necessary in conveniently controlling movements on part of the gate. Further, the weighted member serves to press the finger 15 into engagement with the link connection 11, and thus renders the locking action of the latter exceptionally strong and positive. Connected with the bracket 10 is an eye 18 to which is connected a flexible cable or chain 19, the latter leading upwardly and being formed to terminate in diverging portions 20, the ends of which being connected with the adjacent end of pivoted operating arms 21. The latter are pivotally mounted as at 22 upon upright posts 23, disposed upon both sides of the gate, and the arms are so arranged as to lie substantially parallel with the roadway 6. The

other ends of the arms 21 are provided with depending operating chains 24, which terminate in hand engaging portions 25, so disposed as to be conveniently grasped by one traveling upon the roadway 6.

It will thus be seen, from the foregoing description, that when the gate is desired to be swung from a closed to an open position, the chain 24 of either arm is pulled downwardly thus causing both of the arms 21 to oscillate in unison. This results in the elevation of the cable 19 and in the consequent vertical oscillation of the member 9. Then through the link connection 11, horizontal swinging movement is imparted to the gate structure B. It will be appreciated that oscillating movement on part of the member 9, causes the finger 15 to be released from engagement with the link connection 11, thus rendering the gate capable of swinging to an open position. Owing to the weighted construction of the member 9 it is impossible for the latter to strike a central standing position when being oscillated, but on the other hand is obliged to travel from one position of oscillation to the other. As shown in Fig. 3, when the gate is open, the member 9 will engage with the end of the frame 7, so that further movement on part of the gate will thus be prevented. When occupying this latter position, the link connection 11 is so disposed as to prevent accidental closing movement on part of the gate, and as a matter of fact the gate is only capable of being operated by means of the pivoted arms 21. It will thus be appreciated that a vehicle driver when approaching the gate may open the latter by simply oscillating one of the arms 21, then after passing by the gate the latter may be closed by oscillating the other co-operative arm 21, thus relieving the driver of the necessity of getting out of his vehicle to move the gate from one position to the other. This feature being particularly desirable during periods of inclement weather. While I have described the above construction in connection with a particular form of gate, it will be appreciated that the mechanism A in reality simply constitutes a gate attachment, and may therefore be used in connection with all gates of a swinging type.

I claim:

The combination with a gate mounted for swinging movement and situated, when in closed position, to extend transversely of a roadway, of means for effecting the opening and closing of said gate comprising a member pivotally connected at one end for oscillatory movement with a fixed anchorage located adjacent the roadway, a weight carried by the opposite end of said member, a depending bracket carried by said member intermediate its ends, a link pivotally connected to the lower end of said bracket at one

end and at its other end to said gate, a depending structure carried by said member intermediate its weighted end and said bracket to engage the link intermediate its 5 ends to prevent elevation of the end of the link connected with said bracket when the gate is in closed position by a push upon the

gate, and means located adjacent the roadway for elevating the weighted end of said member whereby opening movement is im- 10 parted to the gate through the link.

In testimony whereof I affix my signature.

IRA D. BATE.
